UNITED STATES PATENT OFFICE.

JOHN E. PARRISH AND RICHARD HALE SMITH, OF SPRINGFIELD,
MASSACHUSETTS.

SPEED-INDICATING AND ALARM DEVICE FOR VEHICLES.

No. 801,605.

Specification of Letters Patent.

Patented Oct. 10, 1905.

Application filed October 31, 1904. Serial No. 230,830.

To all whom it may concern:

Be it known that we, JOHN E. PARRISH and RICHARD HALE SMITH, citizens of the United States of America, and residents of Springfield, in the county of Hampden and State of Massachusetts, have invented certain new and useful Improvements in Speed-Indicating and Alarm Devices for Vehicles, of which the following is a full, clear, and exact description.

This invention relates to improvements in speed-indicating and alarm devices for vehicles, and more particularly available on automobiles, to enable the person who may control the vehicle to know when the permissible speed limit is reached or exceeded.

The improved indicator and alarm device pertains more particularly to the kind which includes a centrifugal governor driven at a speed proportionate to that of the vehicle and parts coöperative therewith for actuating the indicator and alarm devices, although under certain aspects of this invention the indicator-actuating means may be constituted by mechanism other than a centrifugal governor.

An object of the invention is to produce a speed-indicator employing a centrifugal governor which is of simplified construction and direct as regards the connection between the governor and the indicator.

Another object of the invention is to acquire a novel and particularly advantageous combination of automatic indicator and illuminating means therefor, the latter preferably consisting of an electric lamp and having means for its energizing and control and available as convenience may require.

Another object of the invention is to provide as a new and highly advantageous arrangement an indicator and illuminating-lamp therefor and means for establishing the lamp-circuit at pleasure and, further, means for automatically establishing the lamp-circuit when the speed limit is reached.

Another object of the invention is to provide a new arrangement of instrumentalities for operating an audible signal or alarm when the speed limit is reached and to regulate the same so that by a prearranged adjustment the sounding of the alarm may be assured when a predetermined speed limit is reached.

Another object of the invention is to acquire a simplified, reliable, compact, and economical arrangement of the electrical devices pertaining to a lamp and audible signal, whereby one

battery or generator and certain of the circuit connections may serve in common in the electrical efficiency of both the lamp and the signal.

Another object is to render the device in its entirety readily adaptable for employment on automobiles having different sizes of wheels and with no required change beyond the substitution of the indicator card or cards prepared to correspond with the various diameters of wheels for various makes of automobiles.

Another object is to provide improved means for attachment of annular gear-wheels of different sizes (employed for transmitting movement and power to the indicator-governor) on and concentric with the hub of one of the driven traction-wheels of an automobile, enabling the speed-actuating means therefor to be readily applied on any vehicle, as may be required.

Further and minor objects of the invention will be found to be attained in the organization and details of construction of the mechanism as hereinafter specifically described; and the invention consists in the various combinations and arrangements of instrumentalities and the specific combinations of parts and constructions of certain of the parts, all substantially as hereinafter fully described, and set forth in the claims.

The improved speed-indicator and alarm is shown in the accompanying drawings, in which—

Figure 1 is substantially a central sectional view of the main portion of the device. Fig. 1^a is a cross-sectional view as taken horizontally on the line *a a*. Fig. 2 is a vertical sectional view of an upper portion of the device as taken at right angles to the corresponding portion shown in section in Fig. 1. Fig. 2^a is a perspective view of parts in detail, hereinafter mentioned. Fig. 3 is a plan view with an upper portion shown in horizontal cross-section. The section-lines 1 1 and 2 2 on Fig. 3 respectively represent the planes of the sectional views Figs. 1 and 2. Fig. 3^a is a detail representation of the mounting of the pointer on the indicator-stem. Fig. 4 is a perspective view having the nature of a diagram, illustrating the electrical appliances and equipments. Fig. 5 is a perspective view of the indicator and alarm device in its external aspect. Figs. 6 and 7 are front and side views.

of the detachable casing for holding the indicator-cards and within which the indicator-pointer and circuit-closing devices are contained. Fig. 8 is a perspective view showing 5 appliances pertaining to the power-transmitting connections between a wheel of the vehicle and the indicator.

Similar characters of reference indicate corresponding parts in all of the views.

10 In the drawings, A represents a casing for inclosing the indicator-governor B, the audible alarm or signaling device C, and the battery D and having as a detachable upper part thereof the supplemental case E and also 15 supporting within the apertured hood F at its upper portion the electric lamp G, and said casing A for fitness to its purpose is made in upper and lower generally cylindrical sections b and c, the one being constructed with 20 the depending pockets d and e for the reception therewithin of the battery and the audible signal or alarm, which in the present instance may be the well-known electromagnetic buzzer, comprising a circuit-breaker, 25 as common in this familiar kind of buzzers and in electric bells.

The main casing A has at its top a central socket f for the reception therewithin of the depending hollow boss g, which forms a lower 30 integral part of the indicator-casing E, which indicator-casing has downwardly-terminating vertical slots h and i through its front and side walls, and its front is formed with inner and outer pairs of vertical downwardly-opening 35 ing opposite grooves 10 and 12 for the reception therein of the indicator-card j and a protective pane of glass k.

The indicator-casing in its construction or design has top and opposite edge walls 13 and 40 14, 14 standing out forwardly beyond the wall 15, through which the downwardly-opening vertical slot h is provided for the movements of the stud m, which carries the index or indicator pointer n closely outside of the 45 indicator-card and the aforesaid casing-wall 15 and behind the protective glass k.

The stud-screw 16, penetrating the side wall of the socket f, securely holds the indicator-casing in its place and in connection with 50 the top of the main casing A. The upper and lower sections b and c of the main casing are matched together with an encircling rabbet-joint, as indicated at 17, and confined by set-screws 18.

55 The lower wall of the socket f and the bottom wall at the center of the main casing have axially-alined journal-openings 19 and 20 for the bearings for the rotary governor-spindle o, said spindle protruding below a bearing-wall 60 of the casing for connection with the flexible shaft H, and it has the upper and lower thrust-collars 21 and 22, the latter being adaptable to bottom against a washer 23, of leather or other suitable material, which 65 is fitted in the socket 24 in the bottom wall of

the main casing. The governor-spindle has the upper pair of ear-lugs 25, to which the weight-carrying governor-arms 26 are pivoted, while the lower portion of the governor-spindle is encircled by the yoke 27, to which 70 the link members 28 of the governor are pivotally connected, the link members being also pivotally connected to the arms 26, which carry the governor-weights 29. The governor-spindle o is formed tubular from a point 75 toward its lower end, the axial passage therein being upwardly open into the indicator-casing, and the indicator-stem q, longitudinally and vertically movable in the tubular governor-spindle, is at its lower end by cross-pin 32 connected to the yoke 27. The tubular spindle for a suitable portion of its length is slotted through its opposite sides, as represented at 33, for the free vertical play of the connected, governor-yoke, the cross-pin, 80 and the indicator-stem. The indicator-stem at its upper end has the indicator-head r so connected thereto that such head moves vertically bodily in unison with the stem, but without partaking of the rotary motion which 85 such stem has in consonance with the governor, and the supporting connection between the head and stem is made by the provision of a hole centrally and vertically through the head to loosely fit over the necked-down upper portion of the stem and against the stem-shoulder 35, while the confinement of the head against displacement is made by the nut 36, which screws on the still further attenuated upper extremity of the stem and bottoms 90 against the upper stem-shoulder 37 and without binding the indicator-head. This detail of construction is represented in Fig. 3^a. The head supports the aforementioned lateral stud m, which projects through the slot in the 95 front of the indicator-casing and through the slot in the indicator-card and carries the double-armed index or pointer n at its extremity, which protrudes slightly beyond the front face of the card. 100

The indicator-card j, having the slot leading from a point only a short distance above its upper edge down to its lower edge, has the figures for indicating speed of miles per hour arranged, as shown, staggered or in different 105 horizontal planes at the opposite sides of the slot to enable the employment of comparatively large and easily-visible speed-indicating figures in the space on the card therefor, so that the ends of the double-armed pointer 110 in the rising of the index will alternately register with figures on the opposite sides of the card.

Within the hooded opening through the top of the casing and to one side of the location 115 of the indicator-case is disposed the incandescent electric lamp G, which is carried in a metallic socketed holder 40, that is set on a metallic plate 42, riveted on the upper side of the block 43 of fiber or other suitable insu- 120 125 130

lating material. Said block of fiber, made of step form, as shown in Fig. 4, is supported next below the top wall of the main casing A A by the screw 45, which passes through the 5 screw-hole 46 in the thickened part of the block 43 with a screw-thread engagement in the top wall of the casing. Secured on the said block 43, of insulating material, is an angular metallic plate 48, comprising the 10 spring-tongue 49, which extends over and is normally out of contact with the metallic plate 42, and also comprising the vertical bar-like member 50, which has its location within the indicator-casing parallel with and back of the 15 indicator-stem *g*.

52 represents a contact member formed as a part of a clip 53 in metallic contact against the vertical member 50 of the aforementioned plate 48 and adjustable vertically thereon. 20 This contact has its vertical adjustment variously high relatively to the indicator-head *r*, in order that the electric circuit may be established as may be required to sound the buzzer or to both sound the buzzer and energize 25 the electric lamp for its illumination, and it will be perceived with reference to Figs. 2, 3, and 4 that the swell portion 52, which directly makes the contact, is in such proximity to the indicator-stem *g* and path of movement 30 of the head *r* that the latter when sufficiently elevated may rub against and past the adjustably-set contact 52.

For the positioning adjustably of the contact 52 and the accurate determination of such 35 positioning the contact-clip 53 is connected with a block 55 of insulating material, which has embedded or set in it the stud 56, which protrudes through the vertical slot *i* in the head of the indicator-casing, engaging through 40 the perforation centrally in the body of the pointer *t* and receiving at its screw-threaded outwardly-protruding extremity the binding thumb-nut 58. The pointer-body *t* has the upper and lower inwardly-extending ears 59, 45 which engage in the opposite walls of the slot *i* and prevent the pointer from turning and also serve to guide the pointer in its vertical movements of adjustment.

The card *u* has the series of mile-speed numbers, relatively to any one of which the contact may be set by moving the parts adjunct thereto and just described as permitted by the loosening and resetting of the binding thumb-nut.

55 60 represents a circuit-closing spring-tongue or contact-strip which has one end thereof screwed at 62 to the top wall of the main casing A and its free extremity normally separated from the aforementioned metallic plate 42 and adapted to be forced to contact against said plate by the depression of the push-button *v*, which is set within and guided through a socket therefor in the top of the main casing. This push-button may be made as a knob of

suitable material affixed at the free extremity 65 of the spring-tongue.

66 represents a spring strip or tongue having one end secured to the under side of the main case by the screw 65 and having its free end extending over the aforementioned contact-tongue 49, formed as a part with the plate 48 and the upstanding strip 50. The screw having the knurled head and represented at *w* for engagement through a threaded perforation in the top wall of the main case 75 has its lower end next over and against or close to the spring-strip 66, which spring-strip, it may be here stated, is constituted of semi-rigid celluloid or other suitable material of an insulating character, so that by its inter- 80 posed relation between the screw *w* and the contact-making metallic tongue 49 there can be no short-circuiting when the tongue 49 is in contact against the plate 42 between such plate and the metallic main case A, to which 85 the electric wire conductors, to be hereinafter shortly pointed out, have "grounding" connections, whereby the metal of the casing is rendered a part of the conductors for the 90 buzzer and lamp circuits.

95 While the circuits may be constituted and arranged, in the light of the stated functions in the carrying out of this invention as herein disclosed, in various ways which would be obvious to the electrician, the particular composition of the circuits will be pointed out as follows: From the pole 70 of the battery the wire 72 runs to connection with one terminal 73 of the buzzer, having the electro-magnets 74 and including for the armature 100 the flat buzzer-spring 75, and from the other terminal 76 of the buzzer the wire 77 runs to connection with the binding-screw 78, which is in metallic connection with the plate 48, the contact-point 49, and the upstanding strip 105 50. The other pole 80 of the battery is by wire 82 continued to a grounding connection at 83 with the case A, and in metallic connection or grounding connection with which case is the indicator-head *r* through its stem and 110 the governor-spindle. Now with regard to the circuit for the buzzer only it will be perceived that as the indicator-head *r*, comprised in metallic contact in the circuit in question, rises sufficiently high and touches the contact 115 52 the course of the current will be from the battery through wire 72 to and through the buzzer, thence by 77 to and through the plate 48, strip 50, indicator-head *r*, through the case A and by the return wire 82 from the case 120 back to the battery. Thus if the pointer *t* is adjusted and fixed to register with the figure "15" on the alarm-card *u* the arrangement will be for the closing of the circuit and the sounding of the buzzer when the running 125 speed of fifteen miles per hour through the governor causes the elevation of the indicator-head to the height which brings it to

contact with the part 52 for closing this circuit, and as regards the circuit for the lamp, which may be automatically established concurrently with the closing of the buzzer-circuit and also to be established at pleasure and independently of the closing of the buzzer-circuit, it will be pointed out that the metallic socket or casing 40 for the lamp and with which, as common, one filament-terminal is connected rests upon and is soldered to the aforementioned metallic plate 42, while the other filament-terminal of the lamp, as also common, is continued by the rearwardly-extending spiral spring 90 to the upstanding member 92 of the angular plate, the base 93 of which is secured, as by riveting, to the under side of the insulating supporting-block 43. The metallic plate 42 on the top of the insulating-block is therefore in electrical connection with one terminal of the lamp and thoroughly insulated from the other terminal of the electric lamp, with which other terminal the metallic part 92 93 is in metallic connection, and with said angular metallic part 92 93 the branch 72^a of the wire 72, heretofore referred to as running from one pole of the battery to one terminal of the buzzer, has connection at the binding-screw 94. Now preparatory for the automatic or the manual establishment of the lamp-circuit or for both manners of its establishment the screw *w* is turned down, so that the spring-tongue 49 of the plate 48, included in the connections for the buzzer-circuit, is forced, through the medium of the interposed elastic strip 66, to contact against the plate 42, and when the indicator-head *r* rises to touch the contact 52 the current traced in circuit, as aforesaid, from the battery through the buzzer and plate 48, &c., will have a portion thereof branched through wire 72^a, angular plate 92 93, through the lamp to plate 42, and by way of the spring-tongue 49, plate 48, upstanding strip 50, indicator-head to the casing, and through the casing and by the return-wire 82 back to the battery, and whenever through the push-button *w* the plate 60, which is in metallic connection with the casing, electrically joins the casing with the aforementioned plate 42 the lamp-circuit is in the second manner established and as may be done at any time, irrespective of the running speed of the automobile, by creating conditions for the current to pass from the battery by wire 72^a, through the lamp to plate 42, thence by the contacting tongue 60 to the case, through which it passes to the return-wire 82, and back to the battery. In the day-time the screw *w* would be turned up to permit the tongue 49 to spring away from the plate 42 and render the means for automatically establishing the lamp-circuit inoperative and for conserving the battery, and, again, when dark and the screw *w* is turned down, and even while the

automobile may be running comparatively slowly, the person in control by depressing the push-button may secure a temporary illumination of the face of the indicator from the lamp for perceiving what indication of speed miles the indicator-pointer is giving. 70

The transmission of the power from the driven wheel *J* of the automobile to the governor-spindle *o* of the indicating device, which device is supported, by means of the lug *w*, on any available front portion of the vehicle-body is through means of the rim gear-wheel *K* to the pinion-gear *L* in mesh therewith, to the pinion-gear shaft or arbor *M*, to the flexible shaft *H*, which is secured at one end to the pinion-arbor and at its other end to the governor-spindle, as represented in Fig. 1. 75

With reference to Fig. 8, the rim-gear, made in the form of an annulus and hubless, is attached, preferably, at quarters to surround concentrically the hub of the automobile traction-wheel *J*, and the connection and adjustment of the rim-wheel *K* is accomplished by the provision of the clips *O*, one of which is represented in said Fig. 8 as consisting of a single length of half-round wire 90 formed with an intermediate loop 85 to encircle a spoke 86 and with its extremities 87 adjoined and extended through a hole in the rim-gear, such extremities being screw-threaded and receiving a confining-nut 88, 95 which sits against the inner face of the rim-gear. The rim-gear may have a widened boss at its portion through which the sidewise-adjoined portions of the clip pass for the purpose of affording sufficient length of bearing-support for the clip-shank with corresponding stability. By removing the nuts 88 the clips may be drawn away from and out of connection with the rim-gear, and the clips may by spreading the separable adjoined extremities be disengaged from the intermediate portions of the spokes, the reversal of these actions of course permitting the adjustment and connection of the gear-wheel on the traction-wheel. The mounting and adjustment of the pinion *L* in connection with the flexible shaft on any available support therefor—as, for instance, on a member of the steering-knuckle in part represented at *P*—and for the proper positioning and perfect meshing of the pinions with the rim gear-wheel is accomplished by the equipments as follows: A clamp or clip *Q* for detachable connection with the support *P* therefor has the upwardly-extending elongated boss 190, having the upwardly-open socket 192 therein, in which fits for vertical adjustment the stem 193, formed as a part of and depending below the horizontally-bored head 194, through which the pinion-arbor *M* has a journal-bearing for rotation. The pinion-arbor has collars 95 95 adjustable thereon at opposite ends of the head 194, through which the arbor is journaled, said collars be- 100 105 110 115 120 125

ing confined as adjusted by the set-screws 96 96, which screw transversely through them and against the periphery of the pinion-arbor. The stem 193 is held in its proper adjustment 5 height by the set-screw 97. The pinion-arbor support as a whole may be bodily adjusted in directions toward or away from the wheel-axis and also rocked to bring the pinion in the coinciding plane with the rim-gear by sliding 10 and rocking movements of the clip *g* relatively to the steering-knuckle or other support *P* therefor. The pinion may be raised or lowered by moving the stem 93 in the socketed boss 90, the set-screw 97 being loosened 15 and afterward reset for this adjustment, and the pinion-arbor *M* may have an axial movement, so that the width of the pinion properly matches with the width of the rim-gear by loosening the collars 95 95 and sliding 20 the arbor through the journal-bearing head 194, carried at the top of the vertically-adjustable stem 193. There is the further capability of adjustment by giving the stem of the journal-bearing head a swiveling movement 25 in its socket.

The devices described and illustrated in Fig. 8 are to be provided by the manufacturer of the indicator device to accompany and form a part of such device and to render the latter 30 susceptible of convenient utilization by any owner of an automobile, and in cases where the automobile has traction-wheels of size different from the most common twenty-eight-inch wheels it is only necessary in setting up 35 the indicator to place one of the cards with the indicating-numbers graded to accord with the thirty-inch or other diameter of the traction-wheels in the front of the indicator-casing *E*, at the same time supplying a correspondingly-graded automatic speed-alarm 40 card *u* at the rear sidewise portion of the indicator-casing, which casing, as hereinbefore stated, is detachable from the main governor-containing casing and capable of being removed 45 without disturbing the indicator head and pointer by lifting it out from its socket *f*, as may be done by loosening the set-screw 16 after the top section *b* of the main case has been slightly separated from the section *c*, or 50 by having the screw 16 sufficiently long and externally accessible, as indicated by dotted lines in Fig. 1, the detachment of the indicator-case may be accomplished without opening the governor-casing.

The bottom wall of the pocket *d* may be made separable from the main casing *A*, so as to be temporarily opened to permit the battery to be drawn downwardly out from the casing and without disturbing the mechanism 55 or equipments of the indicator device, thus enabling the battery to be replaced or removed for the purpose, as occasion might require.

As made clear by dotted-line indications in 60 Fig. 1, the sectionally-made closing bottom wall

of the pocket *d* may be hinge-connected to the side wall of the pocket and the confinement of this closing section made by a bolt or set-screw 99, passed through a lug 100, and an ear 102 provided to the parts and in the arrangement shown in Fig. 1.

The indicator might be constructed without departing from certain aspects of the present invention, with the inclusion of means other than a centrifugal governor, as shown, as the 70 actuator for automatically imparting the appropriate movements to the indicator-pointer and the part which closes the circuit for illuminating the lamp, for sounding the audible alarm, or for either or both of these results, 75 and various other changes and modifications of a minor character and pertaining to details of construction and arrangement may be made in accordance with and without departing from this invention.

Variable resistance to the action of the governor and the resultant elevation of the indicator-carrying stem is rendered possible in the device by the provision of the spring 31, which encircles the governor-spindle and is in 80 greater or less compression between the yoke 27 and the adjustable collar 31^a. In the setting up of the mechanism the collar is to be moved up or down on the spindle and set properly to establish governor-controlling conditions which may be relied upon for accurately-uniform speed indication.

Having thus described our invention, what we claim, and desire to secure by Letters Patent, is—

1. In a speed-indicating device, the combination with a casing, having a centrifugal governor, therein, provided with a hollow, upwardly-open, spindle, and having at its top a supplemental indicator-casing having a slot 105 through the wall thereof, and which casing is also constructed for the reception of interchangeable cards, of a stem within the hollow spindle, subject to vertical movement on the operation of the governor, and having its upper end located in the indicator-casing and having a part movable closely to, and registering on, the indicator, and means connected with the governor for imparting its rotation thereto.

2. In a speed-indicating device, the combination with a circular inclosed casing having upper and lower central journal-bearings, and made with a socket about the upper journal-bearing, and a centrifugal governor in 120 said casing provided with a hollow upwardly-open spindle and mounted for rotation in said journal-bearings, of a supplemental downwardly-open, indicator-case, having a hollow lower part fitted and detachably confined in 125 said socket and having an indicator-scale, a stem within the hollow spindle, subject to vertical movement by the operation of the governor, extended upwardly within the indicator-case and having an externally-visible 130

part movable closely to, and registering on, the indicator-scale.

3. In a speed-indicating device, the combination with a circular inclosed casing having 5 upper and lower central journal-bearings, and made with a socket about the upper journal-bearing, and a centrifugal governor in said casing provided with a hollow upwardly-open spindle and mounted for rotation in said 10 journal-bearings, of a supplemental, endwise-open, indicator-case, having a hollow downwardly-open boss at its bottom fitted and detachably confined in said socket, and having a vertically-slotted front wall made with 15 opposite endwise-open grooves, and a vertically-slotted indicator scale-card on the front wall of the indicator-case, and marginally engaged in said grooves, a stem within the hollow spindle, subject to vertical movement by the operation of the governor extended upwardly within the indicator-case and carrying a pointer at its upper portion extended through the slots of the indicator-case and scale-card, and arranged closely to, 20 and registering on, the card.

4. In a speed-indicating device, the combination with the main governor-casing supporting at its top an indicator-casing having a slotted front and a slotted scale-card thereat, 30 and a centrifugal governor in the main case provided with a hollow upwardly-open spindle, of a stem within the hollow spindle, connected with the governor, rotatable in unison therewith, and endwise movable independently 35 of the governor-spindle, and having at its upper end an indicator-head, bodily movable with the stem, and relatively to which the stem is independently rotatable, and said head having the lateral stud projecting through 40 the slots of the indicator-casing and scale-card, and a pointer carried, adjacent the face of the scale-card, by the outer extremity of said stud.

5. In a speed-indicating device, in combination, the main governor-casing of circular form, and inclosed, having journal-bearing holes through its top and bottom, and having about the upper journal-hole an upwardly-open socket *f*, the surrounding wall of said 50 socket depending within the top of the casing, and said main casing being constructed of the upper and lower matching sections *b* and *c*, the indicator-casing having a downwardly-open depending boss fitting in said socket, 55 and having a vertically-slotted front wall provided with an indicator-scale detachably connected thereat a set-screw engaging said hollow boss through the wall of the socket therefor, a centrifugal governor having the spindle thereof hollow, upwardly open, and longitudinally slotted, through its sides, the indicator-stem vertically movable within the indicator-spindle and connected with a movable member of the governor, and a head carried 60 at the upper end of the stem within the indi-

cator-casing, provided with the lateral stud projecting through the slot in the indicator-case and having the externally-located pointer.

6. In a speed-indicating device, the combination with an inclosed governor-casing having at its top a supplemental endwise-open indicator-case, having a vertically-slotted front wall with side-wall extensions forwardly projecting beyond the slotted front wall and having within their inner sides the opposing pairs of grooves 10 10 and 12 12, the slotted indicator-card engaged in the grooves 10 and the glass forward thereof marginally engaged in the grooves 12, of the governor, having an indicator-stem endwise movable relatively 80 thereto and actuated thereby, provided at its upper end, within the supplemental case, with a part projecting through the front-wall slot and provided with a pointer to register on the card. 85

7. In a speed-indicating device, a governor-casing having at the top thereof an indicator-scale, a governor in said case and a stem actuated by the governor and having a pointer registering on the scale, an electric lamp supported on the case, adjacent, and to illuminate, the scale, normally open circuit connections for the lamp including a battery, and means, comprised in the lamp-circuit, and movably controlled by the governor for automatically closing the lamp-circuit under predetermined speed conditions and additional, and non-automatic, means for closing the lamp-circuit at pleasure. 90

8. In a speed-indicating device a governor-casing having at the top thereof an indicator-scale, a governor in said case and a stem actuated by the governor and carrying a pointer having a reciprocatory movement and registering on the scale, an electric lamp supported on the case, adjacent, and to illuminate, the scale, and an audible electrically-operable signaling device, normally open circuit connections comprising a generator, and connecting the lamp and the signaling device, and a 100 movable part controlled by the governor for closing the lamp and signal circuits, for simultaneously lighting the lamp and sounding the alarm, under predetermined speed conditions, and additional, non-automatic, means, 105 for closing the lamp-circuit at pleasure. 110

9. In a speed-indicating device, a governor-casing having at the top thereof a supplemental casing having an externally-visible indicator-scale, and having a vertically-slotted wall, a 120 governor in said case and a stem actuated by the governor and having a head in the supplemental case provided with a pointer registering on the scale, an electric audible alarm device, normally open circuit connections for the alarm device, including a battery, the head of the indicator-stem and an adjustably-movable contact relatively to which the head of the governor-controlled stem moves, and by a screw-stud projected through the slot in the casing, 125 130

- and having a confining-nut, and controlling the position of said adjustable contact, for the purposes set forth.
10. In a speed-indicating device, a governor-
5 casing having at the top thereof a supplemental casing having an externally-visible indicator-scale, and having a vertically-slotted wall, a governor in said case and a stem actuated by the governor and having a head in the supplemental case provided with a pointer registering on the scale, an electric audible alarm device, normally open circuit connections for the alarm device, including a battery, the head of the indicator-stem, and an adjustably-movable
10 contact relatively to which the head of the governor-controlled stem moves, a screw-
15 stud projected through the slot in the casing and having a confining-nut, and controlling the position of said adjustable contact, a numbered scale on the side of the casing adjacent said slot, and a pointer, engaged with the screw-stud, and movable therewith along said slot and for registry on the numbered scale, for the purposes set forth.
- 20 11. In a speed-indicating device, a governor-
25 casing having at the top thereof a supplemental casing having an externally-visible indicator-scale, and having a vertically-slotted wall, a governor in said case and a stem actuated by
30 the governor and having a head in the supplemental case provided with a pointer registering on the indicator-scale, an electric audible alarm device, and an electric lamp adjacent the indicator, normally open circuit connec-
35 tions for the alarm device, and for the lamp including a battery, the head of the indicator-
40 stem, and an adjustably-movable contact relatively to which the head of the governor-con-
trolled stem moves, and means for connecting and disconnecting the circuit connections per-
taining to the lamp from those pertaining to
the alarm device.
- 45 12. In a speed-indicating device, a governor-
50 casing having at the top thereof a supplemental casing having an externally-visible indicator-scale, and having a vertically-slotted wall, a governor in said case and a stem actuated by the governor and having a head in the supplemental case provided with a pointer register-
55 ing on the indicator-scale, an electric audible alarm device, and an electric lamp adjacent the indicator, normally open circuit connec-
60 tions for the alarm device, and for the lamp, including a battery, the head of the indicator-
65 stem, and an adjustably-movable contact relatively to which the head of the governor-con-
trolled stem moves, and means for connecting and disconnecting the circuit connections per-
taining to the lamp from those pertaining to
the alarm device, and additional, and non-automatic, means for closing, at pleasure, the lamp-circuit.
- 70 13. In a speed-indicating device, a governor-
75 casing provided with externally-visible indi-
cator-scale, and having a vertically-slotted wall, a governor in said case and a stem actu-
ated by the governor and having a head in the supplemental case provided with a pointer register-
80 ing on the indicator-scale, an electric audible alarm device and a battery, a metallic plate mounted on an insulating-support, having connection with the electric alarm de-
vice and having an upstanding member with-
in the supplemental casing adjacent the indi-
85 cator-stem, a contact vertically movable on
said upstanding member and having an insu-
lated stud projecting through the slot of the supplemental casing, a wire connecting said plate and the battery, a wire connecting the battery with the metallic governor-casing, and metallic connections between the governor-
90 casing and the contacting head of the indi-
95 cator-stem.
14. In a speed-indicating device, a governor-
100 casing having at the top thereof a supplemental casing provided with an externally-visible indicator-scale, and having a vertically-slotted wall, a governor in said case and a stem actuated by the governor and provided with a pointer register-
105 ing on the indicator-scale, an electric lamp and an insulating-support se-
cured within the casing having a metallic plate 42 thereon, and on which the metallic socket of the lamp is in contact, an independent me-
tallic plate 92, 93, secured to said support and with which one terminal of the lamp is in me-
tallic connection, the battery, wire connected to said metallic part 92, 93, and wire connected to the metallic governor-casing, and a tongue 110 adjacent and normally separated from the me-
tallic plate 42, and in connection with the elec-
trically-conducting governor-case, and means for forcing said tongue against plate 42, for
the purposes set forth.
15. In a speed-indicating device, a governor-
115 casing having at the top thereof a supplemental casing provided with externally-visible indicator-scale, and having a vertically-slotted wall, a governor in said case and a stem actu-
ated by the governor and having a head in the supplemental case provided with a pointer register-
120 ing on the indicator-scale, an electric lamp, and an insulating-support therefor se-
cured within the casing having a metallic plate 42 thereon, and on which the metallic lamp-
socket is in contact, an independent metallic plate 92, 93, secured to said support and with which one terminal of the lamp is in metallic connection, the metallic part 48 having the 125 upstanding member 50, and the tongue 49, extending to overlap, normally separated from, the plate 42, a contact supported by, and adjustable on, the member 50 in electrical connection with the part 48, and also con-
nected to the metallic governor-casing, me-
tallic connections through the governor be-
tween the governor-casing and the indicator

stem and head, and means for placing the tongue 49 in contact against the plate 42 for the purposes set forth.

16. In a speed-indicating device, a governor-
5 casing, having at the top thereof a supplemental
casing provided with an externally-visible
indicator-scale, and having a vertically-slotted
wall, a governor in said case and a stem actuated
10 by the governor and having a head in
the supplemental case provided with a pointer
registering on the indicator-scale, an electric
lamp and an insulating-support secured within
the casing having a metallic plate 42 thereon,
15 and on which the metallic lamp-socket is in
contact, an independent metallic plate 92, 93,
secured to said support and with which one
terminal of the lamp is in metallic connection,
the plate 48 having the tongue 49 and the
20 member 50 provided with an adjustable con-
tact adjacent the indicator-stem head, the bat-
tery-wire connected to said metallic part 92,
93, and wire connected to the metallic gov-
ernor-casing, metallic connections through
25 the governor between the governor-casing
and the indicator stem and head, and connec-
tions between the plate 48 and the battery,
means for forcing said tongue 49 against said
plate 42, and the tongue 60 in electrical
30 connection with the case and arranged to be
forced at pleasure against the said plate 42,
for the purposes set forth.

17. In a speed-indicating device, a governor-
casing, having at the top thereof a supplemental
35 casing provided with an externally-visible
indicator-scale, and having a vertically-slotted
wall, a governor in said case and a stem actuated
by the governor and having a head in
the supplemental case provided with a pointer
40 registering on the indicator-scale, an
electric lamp and an insulating-support secured
within the casing having a metallic plate 42
thereon, and on which the metallic lamp-
socket is in contact, an independent metallic
45 plate 92, 93, secured to said support and with
which one terminal of the lamp is in metallic
connection, an electrically-operable audible
alarm device, the plate 48 having the tongue
49 and the member 50 provided with an adjust-
50 able contact adjacent the indicator-stem
head, the battery, wire connected to said met-
tallic part 92, 93, wire connected to the met-
tallic governor-casing, and wire connected
with the audible alarm device and connec-
55 tions between said alarm device and the plate 48,
metallic connections through the governor
between the governor-casing and the indica-
tor stem and head, and means for forcing said
tongue 49 against said plate 42.

18. In a speed-indicating device, a governor-
60 casing, having at the top thereof a supplemental
casing provided with an externally-visible
indicator-scale, and having a vertically-slotted
wall, a governor in said case and a stem actuated
by the governor and having a head

in the supplemental case provided with a 65
pointer registering on the indicator-scale, an
electric lamp and an insulating-support se-
cured within the casing having a metallic
70 plate 42 thereon, and on which the metallic
lamp-socket is in contact, an independent met-
tallic plate 92, 93, secured to said support and
with which one terminal of the lamp is in
75 metallic connection, an electrically-operable
audible alarm device, the plate 48 having the
tongue 49 and the member 50 provided with
an adjustable contact adjacent the indicator
80 stem-head, the battery, wire connected to said
metallic part 92, 93, wire connected to said
metallic governor-casing, and wire connected
with the audible alarm device and connec-
85 tions between said alarm device and the plate 48,
metallic connections through the governor
between the governor-casing and the indica-
tor stem and head, means for forcing said
tongue 49 against said plate 42, and the tongue
90 60 in electrical connection with the case and
arranged to be forced at pleasure against the
said plate 42.

19. In a speed-indicating device, a casing
having a governor therein, an indicator and a
pointer actuated by the governor for regis-
95 tering on the indicator, and an electric lamp, ad-
jacent the indicator, and said casing made with
the pockets *d* and *e* and having a battery and
an audible electrically-operable alarm device,
95 respectively therein, circuit connections com-
prising the battery and the alarm device, and
automatic means controlled by the governor
for closing the circuit for the alarm device.

20. For a speed-indicator the combination
100 with an indicator having a speeding-governor,
of a gear-wheel and detachable means for its
confinement on a traction-wheel of the vehi-
cle, consisting of a clip having its intermediate
105 portion looped to encircle a wheel-spoke
and having its extremities adjoined and ex-
tended through the gear-wheel, screw-threaded,
and having a confining-nut setting against
110 the gear-wheel, a pinion in mesh with the
gear-wheel, and a flexible shaft connecting
the pinion and the governor of the indicator.

21. In transmission connections for a speed-
indicator device of the character described, a
traction-wheel-carried gear-wheel, a pinion
115 to mesh therewith and having an arbor to be
flexible-shaft-connected with the indicator,
and a support for the pinion-arbor, and rela-
tively to which such arbor is adjustable in
the line of its axis.

22. In a speed-indicating apparatus, in com-
bination, a casing carrying an indicator-scale
and having, therein, a governor and a gov-
ernor-controlled stem provided with a pointer
coacting with the scale, a traction-wheel pro-
120 vided with a gear-wheel, a pinion in mesh
with said gear-wheel having an arbor, a flexi-
ble shaft connecting said arbor and the gov-
ernor, and a journal-support for said arbor

which is adjustable bodily in a direction transverse of the axis thereof.

23. In a speed-indicating apparatus, in combination, a casing carrying an indicator-scale and having, therein, a governor and a governor-controlled stem provided with a pointer coacting with the scale, a traction-wheel provided with a gear-wheel, a pinion in mesh with said gear-wheel having an arbor, a flexible shaft connecting said arbor and the governor, and a journal-support, for said arbor, which is adjustable for a swinging movement about an axis perpendicular to the axis of the arbor.

15 24. In transmission connections for a speed-indicator device of the character described, a traction-wheel-carried gear-wheel, a pinion to mesh therewith and having an arbor to be flexible-shaft-connected with the indicator, and a support for the pinion-arbor, and relatively to which such arbor is adjustable on the line of its axis, adjustable bodily transversely of its axis and capable of a swinging movement on an axis perpendicular to the axis of 25 the said arbor.

25. For a speed-indicating device of the class described, the combination with a gear-wheel and a pinion having an arbor, of a supporting appliance and a stem vertically adjustable rela-

tively thereto, and provided with a journal-bearing head in which the arbor of the pinion is rotatably supported and through which such arbor is endwise adjustable, and a flexible shaft secured to the pinion-arbor and for connection with the speeding portion of the 30 indicating device.

26. For a speed-indicating device of the class described, in combination with the indicating device and the vehicle-wheel having a spur-gear K, the separable clip Q having the up-standing socketed portion 190, the stem 193, adjustably confined in said socketed portion and having the journal-bearing head 194, the pinion having the arbor rotatable in, and axially adjustable through, said bearing-head, 40 the adjustable collars 95, 95, and means for adjustably confining them on the arbor at opposite ends of the journal-bearing head and the flexible shaft connected to the arbor and to the speeding portion of the indicating device. 45
